UNITED STATES PATENT OFFICE.

HOMER P. CHANDLER, OF MANSFIELD, OHIO, ASSIGNOR TO THE OHIO BRASS COMPANY, OF MANSFIELD, OHIO, A CORPORATION OF NEW JERSEY.

SUPPORT FOR TROLLEY CONDUCTORS.

Application filed June 3, 1922. Serial No. 565,615.

To all whom it may concern:

Be it known that I, HOMER P. CHANDLER, a citizen of the United States of America, residing at Mansfield, in the county of Rich-
5 land and State of Ohio, have invented cer-
tain new and useful Improvements in a Support for Trolley Conductors, of which the following is a specification.

10 My invention relates to a support for trolley conductors and more particularly to that class of supports known as a trolley clamp or ear.

15 The object of my invention is to produce an ear or clamp which does not require the use of screws, bolts, screw drivers or other tools or fastening devices, as such, to secure the clamp or ear to the trolley wire. I speak 20 of my invention as being a trolley clamp or trolley ear for the reason that it partakes of the nature of both.

25 My invention resides more particularly in the jaw members or lips which directly grip the trolley wire and is due to the resilient character of the lips or jaws, which in turn is due to the property of the material entering into the construction of the lips or jaws.

30 In the drawing accompanying this specification:

Figure 1 is a side view in elevation of my invention shown as positioned on a trolley wire.

Fig. 2 is an end view in partial section.

35 Fig. 3 is an enlarged view of a portion of the jaws or lips which grip the trolley wire and points out particularly the serrated or tooth character of the gripping edges of the jaws or lips.

40 In my preferred construction I employ a body member 1 provided with a boss 2 which is internally threaded in order to secure the supporting device to an overhead support, such as an insulated hanger, etc., commonly used for this purpose. The body member is 45 also provided with an elongated section 3 which in turn has a longitudinal groove 4 adapted to receive the jaw members 5-5. The jaw members are secured in position in the groove 4 by means of rivets or other fastening devices 6. These fastening devices 6 may be removable or permanently fixed in

place, and, as I have shown them, they comprise rivets permanently secured in position.

The jaw members 5-5 are made preferably of a rather thin sheet metal formed to 55 the necessary shape, and this material is preferably ball rolled phosphor bronze which has high resilient qualities, or of steel also having high resilient qualities. The latter material may be either tempered or 60 untempered depending upon the amount of resiliency, stiffness, etc., required which in turn may be effected by the shape and size of the jaw members 5-5. I prefer to make the slot 4 of such width as to receive the 65 molded portion 7 of the jaw members with a snug fit so that there will be no yielding of the portions 7.

In installing my invention upon a trolley 70 wire it may be done by forcing the trolley wire and supporting device directly into engagement thereby causing both jaw members to spread apart and then spring into the groove of the trolley wire after the supporting device and trolley wire have 75 been brought into proper position, or one jaw may be entered in one groove of the trolley wire and then either the trolley wire or the supporting device twisted about the engaging point of the jaw with the trolley 80 wire thereby causing the jaws to spread sufficiently for the entrance of the trolley wire.

In order to eliminate relative lateral movement of my invention with respect to 85 the trolley wire, I serrate the portion 8-8 of the jaws 5 thereby forming small teeth or serrations 9 upon the engaging portion of the jaws which I find will eliminate relative lateral movement of the support and trolley 90 wire. These serrations or teeth 9 may be formed as by means of a stamping die or by means of a chisel cut, the latter producing a slightly raised tooth, while the former will produce a tooth or serration as shown. 95

I find that with the use of proper material in the jaw members 5-5 giving the required elasticity and with the proper gauge of material, that the trolley wire is securely held between the jaws and will resist all of 100 the strains to which the device will be subjected to the removal of the trolley wire, but

it is possible by applying sufficient force to the trolley wire to remove it from the ear thereby being able to again utilize the ear to support another wire.

5. It is quite possible that supporting devices having lips or jaws possessing a resiliency to a degree have been used in the past as nearly all materials which would ordinarily be used in a device of this character, 10 possess some resiliency, but I am not aware that any attempt has been made to utilize the resilient property of the metal exclusively where gripping the trolley wire.

My invention produces a cheap, efficient 15 device and at the same time one which is quickly applied to or removed from the trolley conductor and either of these operations may be effected without the use of tools.

20 There are no doubt modifications which my disclosure will suggest to those skilled in the art and which will fall within the scope of my invention, and therefore I desire not to be limited otherwise than by my claims.

25 I claim:

1. A conductor support comprising a body member provided with means for attachment to a support, a pair of resilient clamping jaws secured within the support 30 and having parts projecting without to grip a conductor, said grip being entirely due to the resilient properties of the projecting part of the jaws.

2. The combination with a body member 35 and means thereon to secure the body member to a support and having means to receive a pair of resilient clamping jaws to grip a conductor of a pair of clamping jaws securely held within said means and having a portion projecting therefrom, said projecting portion arranged to spread apart under pressure to permit the positioning of the conductor therebetween and spring together due to the resiliency of the jaws to 45 engage and grip the conductor.

3. The combination with a body member and means thereon to secure the body member to a support, a pair of conductor engaging jaws formed up out of a resilient 50 sheet material to grip a conductor and having a portion rigidly held in engagement with the body member and having a portion projecting therefrom and free to be forced apart against tension of the jaws to 55 receive a conductor and free to spring into engagement with the conductor due to the tension of the jaws when the spreading face is removed.

4. A supporting device for a conductor 60 comprising a body member having means for attachment to a support and resilient conductor engaging jaws secured to the body member and normally held a fixed distance apart and free to spring back to their

normal position due to their resilient character when a force spreading them apart is removed. 65

5. A supporting device for a conductor comprising a body member, means to secure the body member to a support, and resilient 70 jaws secured to the body member to engage and grip a conductor due to the resilient character of the jaws.

6. A supporting device for a conductor comprising in combination a body member, 75 means to secure the body member to a support, a pair of resilient conductor engaging jaws to grip a conductor, said resiliency forming a component part of the jaws to move them into engagement with the conductor and maintain them in engagement. 80

7. A supporting device for a conductor comprising in combination a pair of unitary cooperating members each having a portion held in rigid engagement with each other and a resilient portion separated from the other and free to move relative to each other to engage and grip a conductor. 85

8. A supporting device for a conductor comprising in combination a pair of jaws 90 having resilient means to move the jaws toward each other to grip a conductor, said resilient means comprising a component part of the jaws.

9. A supporting device for a conductor 95 comprising in combination a pair of holding members having means to secure the jaws to a support and means to engage with and grip a conductor and means on the engaging edge of the jaws to prevent longitudinal movement of the conductor relative to the jaws. 100

10. A conductor supporting device comprising a pair of resilient holding members 105 to engage and grip a conductor and means on the engaging portion of the holding members to prevent relative longitudinal movement of the holding members and the conductor.

11. A conductor supporting device comprising a pair of resilient holding members to engage and grip a conductor and a plurality of serrated-like-means on the engaging portion of the holding members to prevent relative longitudinal movement of the holding members and the conductor. 115

12. A supporting device for a conductor comprising in combination a pair of jaws having resilient means to move the jaws toward each other to grip a conductor, said resilient means comprising a component part of the jaws and means on the gripping edges of the jaws to prevent relative lateral movement of the jaws and conductor. 120

13. A supporting device for a conductor 125 comprising in combination a body member, means to attach the body member to a support and a pair of holding members possess-

ing permanent resiliency and free to engage and grip a conductor due to its resiliency.

14. A supporting device for a conductor comprising a body member, means for securing the body member to a support, a longitudinal slot in the body member, a pair of sheet metal jaws rigidly secured within the slot and having a portion projecting there-

from and means to secure the jaws therein, the projecting portion of the jaws possessing resiliency to return them to a predetermined distance apart after being forced a greater distance apart. 10

In testimony whereof I affix my signature.

HOMER P. CHANDLER.
